UNITED STATES PATENT OFFICE.

JOHN F. DODGE, OF DETROIT, AND HORACE E. DODGE, OF GROSSE POINT, MICHIGAN.

DESIGN FOR AN AUTOMOBILE-FENDER.

48,345.

Specification for Design.

Patented Dec. 28, 1915.

Application filed July 3, 1915. Serial No. 37,970. Term of patent 14 years.

To all whom it may concern:

Be it known that we, JOHN F. DODGE and HORACE E. DODGE, citizens of the United States, residing, respectively, at Detroit and Grosse Point, Michigan, have invented a new, original, and ornamental Design for Automobile-Fenders, of which the following is a clear, full, and exact description.

Referring to the accompanying drawings forming a part thereof, Figure 1 is a side elevation of the fender, showing our new

design; Fig. 2 is a plan of the same; and Fig. 3 is a cross section of the same along line A A, Fig. 1, showing our new design.

What we claim is:

The ornamental design for an automobile fender, as shown.

JOHN F. DODGE.

HORACE E. DODGE.
